(57) **CLAIM**

The ornamental design for an electronic device with transitional graphical user interface, as shown and described.

DESCRIPTION

FIG. 1 is a front view of the first image in a sequence for an electronic device with transitional graphical user interface showing our new design according to a first embodiment where the electronic device is shown in an unfolded state; FIG. 2 is a front view of the second image thereof where the electronic device is shown partially folded inward; FIG. 3 is a front perspective view of the electronic device with transitional graphical user interface of FIG. 1; FIG. 4 is a front perspective view of the electronic device with transitional graphical user interface of FIG. 2; FIG. 5 is a right-side view of the electronic device with transitional graphical user interface of FIG. 1; FIG. 6 is a right-side view of the electronic device with transitional graphical user interface of FIG. 2; FIG. 7 is a front view of the first image in a sequence for an electronic device with transitional graphical user interface showing our new design according to a second embodiment where the electronic device is shown in an unfolded state;

(Continued)

FIG. 8 is a front view of the second image thereof where the electronic device is shown partially folded inward; FIG. 9 is a front perspective view of the electronic device with transitional graphical user interface of FIG. 7; FIG. 10 is a front perspective view of the electronic device with transitional graphical user interface of FIG. 8; FIG. 11 is a right-side view of the electronic device with transitional graphical user interface of FIG. 7; and, FIG. 12 is a right-side view of the electronic device with transitional graphical user interface of FIG. 8. The outermost broken lines in the figures show an electronic device that forms no part of the claimed design. The remaining broken lines in the figures depict portions of the transitional graphical user interface which form no part of the claimed design.

The appearance of the transitional graphical user interface sequentially transitions between the images shown in FIGS. 1 and 2 and in FIGS. 7 and 8, respectively. The process or period in which one image transitions to another forms no part of the claimed design.

The graytones shown in the drawing figures represent a contrast in appearance.
